UNITED STATES PATENT OFFICE.

JOHN W. JARVIS, OF BUFFALO, NEW YORK.

DESIGN FOR A SPECTACLE-CASE OR SIMILAR ARTICLE.

SPECIFICATION forming part of Design No. 35,311, dated November 26, 1901.

Application filed September 9, 1901. Serial No. 74,868. Term of patent 7 years.

To all whom it may concern:

Be it known that I, JOHN W. JARVIS, a citizen of the United States, residing at Buffalo, in the county of Erie and State of New York, have invented and produced a new and original Design for a Spectacle-Case or Similar Article, of which the following is a specification, reference being had to the accompanying drawings, forming a part thereof.

10 This design relates to the configuration of a spectacle-case.

In the accompanying drawings, Figure 1 is a perspective view of a spectacle-case embodying my design. Fig. 2 is a transverse section thereof, taken above its band.

15 Like letters of reference refer to like parts in both figures.

The leading feature of my design consists of a case A of elliptical cross-section, having an oblique mouth *a* at its upper end and a rounded lower end, and a band *b*, encircling the central portion of the case and having beveled upper and lower faces *b'*, which meet at the middle of the band, giving the latter a V-shaped appearance.

20 What I claim is—

The design for a spectacle-case or similar article, substantially as herein shown and described.

25 Witness my hand this 3d day of May, 1901. 30
JOHN W. JARVIS.

Witnesses:

THEO. L. POPP,
CARL F. GEYER.
